UNITED STATES PATENT OFFICE

LEONARD KAY WRIGHT, OF JACKSON HEIGHTS, NEW YORK

REFRIGERATION APPARATUS

Application filed February 6, 1928. Serial No. 252,304.

This invention relates in general to refrigerators and more particularly to a refrigerating apparatus for moving vehicles.

Previous to this time the apparatus used for cooling refrigerator cars and similar vehicles have usually embodied certain fundamental difficulties, which this invention seeks to overcome. The usual mechanisms have been generally not adapted to withstand the shocks incident to transport, as the complicated character of the apparatus has generally made delicate adjustments necessary. This difficulty has been particularly apparent in refrigerating apparatus of the mechanical or absorbent type as the maintenance of a source of power or the storage of the absorbent on a moving vehicle often gives rise to almost insurmountable difficulties. Also the apparatus heretofore employed has usually not been adapted to withstand the effects of wide temperature changes which arise in installations of this kind where the apparatus is constantly being transported to different localities and being subjected to varying climatic conditions.

To overcome the above and other disadvantages inherent in the refrigerating apparatus employed in the past is the foremost object of this invention. More specifically an object of this invention is to provide a self-sustaining apparatus which does not require a motor or other mechanical source of power.

Another object of this invention is to provide a refrigerating apparatus adapted to withstand the shocks and movement of mobile installations.

Another object of this invention is to provide a refrigerating apparatus of the adsorbent type that may be operated by various types of fuel.

A further object of this invention is to provide a process of refrigeration.

To accomplish the above and other important objects, as will more fully appear herein, my invention consists in general means for vaporizing a refrigerant, condensing the vaporized refrigerant, and evaporating the condensate, the combination thereof and a suitable apparatus to be hereinafter more fully set forth and claimed with the understanding

for carrying the same into effect that the necessary elements comprising my invention may be varied in construction, proportion and arrangement without departing from the spirit and scope of the appended claims.

To insure an adequate comprehension of my invention, but wishing it to be distinctly understood that various modifications may be made in the structure herein shown and described without departing from the spirit and scope of my invention, reference is made to the accompanying drawings in which similar numerals indicate corresponding parts:

Figure 1 is a view partly in section and partly in elevation of a refrigerator car equipped with the apparatus forming the subject matter of this invention.

Figure 2 is a partial end view of that part of the car which houses the heating apparatus.

Figure 3 is a top view of Figure 2.

Figure 4 is a view along the line 4—4 of Figure 1, looking in the direction of the arrows.

Figure 5 is a view along the line 5—5 of Figure 1, looking in the direction of the arrows.

Figure 6 is a detailed view of a switch panel.

Figure 7 is a detailed view along the line 7—7 of Figure 5, looking in the direction of the arrows.

Figure 8 is a detailed view in section along the line 8—8 of Figure 1, looking in the direction of the arrows.

Figure 9 is a view along the line 9—9 of Figure 8, looking in the direction of the arrows.

Figure 10 is a detailed view of the adsorbing tank.

Figure 11 is a view along the line 11—11 of Figure 10, looking in the direction of the arrows.

Figure 12 is a perspective view of the refrigerating apparatus.

Figure 13 is a diagrammatic showing of the preferred electrical circuit.

Figure 14 is a sectional view of a modification of the apparatus, the adsorber-generator being omitted from the drawing.

Figure 15 is a partly broken-away view along the line 15—15 of Figure 14, looking in the direction of the arrows.

Figure 16 is a partly broken-away view 5 along the line 16—16 of Figure 14, looking in the direction of the arrows.

Figure 17 shows the preferred method of arranging the evaporating coil in the alternative form of apparatus.

10 Figure 18 shows a modified arrangement of the evaporating coil.

Referring by numerals to the drawings and more particularly to Figure 1, there is shown a freight car having a roof 1 of the 15 hipped type, more fully illustrated, in Figure 2. This roof is provided with the usual running board 2 along its ridge. A rear wall 3, a front wall 4, and side walls 6 and 7 are mounted on a base or floor 5 of the 20 usual construction.

The front wall 4 is screened as at 8 in Figure 2 to permit the entrance of air to that portion of the freight car, and wings 9 and 11, as shown in Figures 2 and 3, are provided 25 on the side of the front wall 4 in order to direct air within that portion of the car. The wings are mounted in such a manner that the air will be directed into the compartment regardless of the direction of movement of the car.

30 A partition 12 is mounted near the front of the car, to effectively shut off a portion of the car from the remainder, and prevent the entrance of air to the interior of the car proper.

35 Doors 13 of the conventional refrigerator type are provided in the walls 6 and 7, which, together with the various walls, and bottom of the car are made of suitable insulating material to prevent a heat exchange, and are of 40 the usual specifications for use in a refrigerating car.

The refrigerating apparatus forming the subject matter of this invention comprises an adsorber-generator tank 14, which it may be 45 seen, referring more particularly to Figure 10, is provided with a cylindrical wall 15, a convex top 16, and a concave base 17. Of course under suitable circumstances a modification of the shape herein shown and described may be made. As will be hereinafter pointed out, heat is applied to the adsorber-generator in order to drive off the refrigerants. It is desirable that the heat be concentrated 50 on the tank 14, and that the loss of heat from the tank be kept as low as possible. The transfer of heat from the adsorber-generator to the rest of the car is of course to be avoided, for it would materially decrease the efficiency 55 of the refrigerating part of the apparatus. To prevent this I have provided a shield 18, composed of asbestos or other heat insulating material, which surrounds the tank 14 and the heating pan beneath the tank, 60 which will be hereinafter described. This

shield prevents the radiation of heat to the rest of the compartment, and concentrates the heat upon the adsorber-generator and its contents.

A crown 19 is secured to the top of the adsorber-generator, as shown more particularly in Figure 10. The crown forms a tight fit with the tank and any heat arising from the top of the tank 14 is confined to the area between the crown 19 and the tank. A funnel 21 is provided in the crown, and extends through the roof of the car. The heat that is given off from the top of the adsorber-generator is therefore conveyed from the interior of the car to the atmosphere where it 75 escapes. A cap 22, shown in Figure 1, is mounted in the top of the funnel 21.

A pipe 23 is joined in a fluid-tight relationship to the top of the adsorber-generator, and extends in a tight fit through the top of the 80 crown 19. This pipe 23 is adapted to convey a refrigerant from the interior of the tank 14 to the rest of the system. It is also the conduit through which the refrigerant passes to the adsorber-generator after the refrigerating 85 cycle.

A wire 24 passes through the crown 19 in a fluid-tight fit, and is joined to a plurality of resistance coils 25, spaced within the tank 14. These coils 25 extend substantially vertically through the tank 14, and form one of the means of heating the tank and its contents. Under certain circumstances, a single coil may be positioned in the center of the adsorber-generator, but it is usually preferable to employ several coils spaced within 95 the tank in order to secure a more uniform dispersion of heat.

Another means of heating the tank, which will be hereinafter discussed, is by applying 100 heat from a source beneath the tank. Ordinarily, the application of heat to the base of the tank would not be desirable, for the length of time required for the heat to permeate the entire tank and its contents, particularly the upper strata, would increase the length of time necessary to secure the most efficient operation of the apparatus. I have therefore shown a plurality of tubes 26, which are welded, brazed, or otherwise suitably secured in the top 16 and base 17 of the adsorber-generator. It will be observed that these tubes extend substantially vertically through the interior of the tank, and permit the passage of hot air from the source of heat, 110 beneath the tank, through the interior of the tank and out at the top. These tubes materially aid the rapid and uniform distribution of heat through the mass of the tank's contents.

Another method of heating the adsorber-generator is by the passage of steam, hot water, or other heating medium through the interior of the tank. I have shown a coil 27, which spirally passes through substantially 115 120 125 130

the length of the adsorber-generator. The coil 27 is supplied with the heating medium from a pipe 28, which passes through the tank in a fluid and heat-tight joint, and as the heating medium flows through the coils the heat transfer effected with the tank's contents is practically uniform through the mass. The extent of the coil, of course, may be varied depending upon the conditions of operation, but I find that the preferable form is that shown in Fig. 10, in which the coiled pipe extends from substantially the top of the tank to the base. A pipe 29, which passes through the wall 15 and shield 18 is either integral with or joined to the coil 27, and conducts the heating medium such as condensed steam from the adsorber-generator.

It is of course obvious that the shape of the channel 27 need not necessarily be in the form of a coil, as shown in Fig. 11, for either a straight pipe or convolutions of a pipe may be substituted for the coil under certain conditions.

The tank 14 is filled with a suitable adsorbent 30 or absorbent, or a combination of both. The exact extent to which the tank is filled with the agent is optional, depending upon the circumstances, but the preferable amount under most conditions practically fills the tank. It will therefore be seen that the tubes 26 and 27, and the resistance coils 25, are totally surrounded by the adsorbent or absorbent. As above pointed out, the arrangement of the various tubings guarantees a uniform and thorough distribution of heat through the mass of adsorbent or absorbent.

As above indicated, a third method of heating the adsorber-generator and its contents is by applying the heat externally to the tank. To carry out this method, I have provided a pan 31, which has an asbestos mat or porous clay tile 32 secured on its base. This pan is positioned immediately below the base 17 of the adsorber-generator. Mounted in the pan is a well 33 which supports a thermostat 34 of a conventional type. This thermostat is provided with a "cold" contact point 35 and a "hot" contact point 36. A finger 37, composed of two strips of metal, having different coefficients of expansion, is secured to a binding post 38. The "hot" and "cold" contact points and the binding post 38 are each joined to wires which form parts of circuits.

The exact electrical hookup will be herein-after described. When the temperature in the vicinity of the thermostat is low, the bimetal finger 37 contacts with the "cold" point 35, establishing one electrical circuit. When the temperature increases the finger 37 bends and contacts with the "hot" point 36, establishing a different circuit.

A jet 39 is mounted in the pan 31 providing a burner for gasoline, kerosene, alcohol or some other suitable fuel. A spark plug 40 of the conventional type is mounted

in the pan adjacent the jet 39, and is supplied with electricity by means of a wire 41. The jet 39 is supplied with fuel through the pipe 42. When fuel is introduced into the jet 39 and dispersed into the atmosphere, the spark plug 40 ignites the fuel. As will be hereinafter set forth the spark plug 40 is controlled by appropriate means to operate only when the fuel first escapes from the jet 39, or if the flame become extinguished.

The pipe 23 conveys a gaseous refrigerant to the tank 14, where it is adapted to be adsorbed or absorbed by the agent with which the tank is filled. The volume of gaseous refrigerant adsorbed is dependent upon the temperature of the adsorbent, and when the adsorbent is at a low temperature a suction is created throughout the refrigerating system, which may be regulated by the valves to be hereinafter more fully described. When the temperature of the adsorbent is lowered, the gaseous refrigerant is drawn into the tank 14, so that it permeates the adsorbent therein. When heat is applied to the tank by any of the systems shown and described herein or by other suitable means, the gas is driven off from the adsorbent and forced to pass out of the tank 14 through the pipe 23.

The pipe 23, as shown in Figs. 4 and 12, is connected to a solenoid valve 44. There is also T'd into the pipe 23 a section of pipe 45 which connects the pipe 23 to another solenoid valve 43.

The gaseous refrigerant is adapted to pass through the valve 44 (when open) into a pipe 46, and thence into a condenser 47. It is manifest that any type of condenser found most suitable for the particular requirements may be employed. In passing through the condenser 47 the refrigerant is liquefied, and is adapted to drain into a storage tank 49 through a pipe 48. It is to be observed that the condenser and storage tank 49 are positioned outside of the body of the car, whereby they are subjected to the temperature of the atmosphere. The wings 9 and 11 aid in this atmospheric cooling, for they direct a current of air onto the condenser regardless of the direction of movement of the car, when the car is in motion.

The storage tank, as shown in Fig. 8, is formed with bulged ends 51 and cylindrical side walls 52. A series of baffle plates 53 are mounted along the length of the tank 49 provided with apertures 54 in the top and base, and mounted in the tank, either by means of soldering or other appropriate methods, as shown in Fig. 9. The plates 53 are positioned in the tank 49 with a space left between the plates and the walls 52 of the tank except at the points 55 when the plates are joined to the walls.

The baffle plates 53 are adapted to prevent any appreciable surging of the liquefied refrigerant from one end to the other

of the tank, such as would ordinarily occur during the movement of a freight car. The plates therefore prevent the wash of refrigerant within the tank and tend to maintain a uniform level of the refrigerant. This not only tends to maintain the apparatus at the highest possible efficiency, but is of particular importance, in connection with the circuit control device, to be hereafter discussed.

10 A well 56 extending above and below the tank 49 and provided with apertures 57 at the top and bottom is suitably mounted in the walls 52 of the tank. A plate 58 is threaded or otherwise fastened on the top of the well, and between the plate 58 and a cap 59 there is clamped a non-conductive bearing plate 61 having a plurality of binding posts or plugs 62, 63 and 64. The plug 63 is formed with an enlarged shoulder 65, and a similar plug, not shown, is provided adjacent the plug 63, between which two plugs there is pivotally supported a mercury tube 66. Wires 67 and 68 connected to the plugs 62 and 64 respectively are fused in each end of the bulb. A wire 71 is connected to the plug 63 and the shoulder 65 is adapted to conduct a current to a contact (not shown) within the bulb 66, which contact may be designated 65'. The mercury within the bulb is designed to establish a contact between the end fused in the bulb of either the wire 67 or the wire 68 and the contact 65'. Wire 67 forms part of one circuit and wire 68 forms part of another circuit, while the shoulder 65 and contact 65' are common to both the circuits. It will therefore be seen that when the bulb is tilted in one direction, one of the circuits will be closed and when it is tilted in the opposite direction the other circuit will be closed.

45 A rod 75 extends through a fused ring 76 on one end of the tube 66 and has beads 77 above and below the ring. Vertical movement of the rod 75 therefore results in a pivoting of the bulb 66 on the supports 65.

50 A float 78 provided with a channel 79 through the center is slidably mounted on the rod 75. The channel 79 is composed of a tube extending in a fluid tight fit through the float 78. A tube 80 extending almost to the base is inserted in a fluid tight fit within the bulb and is adapted to afford an equalization of internal and external pressure, and prevent the collapse of the float.

55 A float 78 shown herein as spherical in shape, although not limited to such form, is slidably mounted on the rod 75. Secured diametrically in the float 78 is a piece of tubing 79, welded, brazed or otherwise suitably mounted in the float in a fluid and pressure-tight fit to afford a channel for the rod 75. The rod 75 extends through this tubing 79, and the relative size of the rod 75 and the channel provided by the tubing 79 is such that movement of the float on the rod is free

and unrestricted within certain limits on the rod.

There is inserted in the float, in a fluid and pressure-tight fit, a tube 80. This tube extends to substantially the base or lowest part of the float, and its external end is bent as at 81. During a refrigerating process there are marked fluctuations in pressures within the system, and considerable difficulty has been heretofore experienced because of these fluctuations. Floats and other hollow vessels with a refrigerating system have frequently been crushed by the high pressures to which they have been subjected. By means of the tube 80 there is maintained an equalization of pressure between the interior and exterior of the float, thus preventing a collapse of the float.

60 In view of the fact that there is an open tube extending into the float there collects to a certain extent vaporized particles of refrigerant within the float, which subsequently condense under an increase in pressure. The bent end 81 of the tube 80 prevents to a certain extent this collection within the float, but does not entirely do away with this objection. The tube 80, however, provides a means whereby the refrigerant within the float may be readily expelled. The condensed refrigerant or liquid refrigerant leaking inwardly frequently immerses the lower portion of the tube. Therefore when the pressure within the system is reduced, as during the evaporating cycle, the higher pressure which has been built up within the float during the heating cycle forces the condensed refrigerant out through the tube. Refrigerant finding its way into the float as the result of a minor leak within the float is 65 also expelled by this tube.

65 It is of course obvious that variations may be made in the shape of this float, although I have found that under most circumstances the spherical form is to be preferred.

70 The float 78 is adapted to rise and fall, on the rod within the limits of beads 82 positioned near the top and bottom of the rod, as the liquid level within the well 56 varies. The float 78 is free to slide on the rod 75 without imparting any motion to the rod until it contacts with either one of the beads. Thereupon movement of the rod causes the mercury bulb to swivel on its pivot, and thus closes the circuit between the wires 67 and 71 when the mercury bulb is tipped to the position shown in Figure 8, or if the mercury bulb is tipped to the reverse position, a circuit between the wires 68 and 71 is established.

75 The liquefied refrigerant introduced into the tank 49 through the pipe 48 is adapted to pass out of the tank 49 by way of the pipe 83, connected to a valve 84 similar to the valves 43 and 44. After passing through the valve 84, the refrigerant enters the pipe 85 by which it is conducted to a secondary receiving tank

86. The receiving tank 86 is suitably secured near the top of the freight car, or other vehicle, and is supported at an angle as shown in Figures 1, 7 and 12. The tank 86, as shown in Fig. 7, is provided with surge plates or baffles 87 similar to the baffles 53 in the receiving tank 49. Upon the base of the lower end of the tank 86 is connected an outlet pipe 88 communicating with a well 89. The well and associated mechanism designated generally as 89 is a duplicate of that in the receiving tank 49, and adapted to operate in a similar manner. The mercury tube in the well 89 is designated 91 to distinguish it later from the tube 66, although the various contacts bear the same numerals as the contacts of tube 66. A pipe 92 provided with a flange 93 bolted to a flange 94 fixed on the end of a pipe 95 extends into a secondary receiving tank 96 similar to the tank 86. The flanges are provided to facilitate the assembly of the apparatus and if desired may be eliminated. The tank 96 is also angularly mounted and slopes in the opposite direction to the tank 86 so that the adjacent lower ends of both of the tanks rest on the same plane. By this arrangement of the tanks 86 and 96, and the position of the pipes, the liquid levels within the well 89 and the tanks 86 and 96 will be the same. A section of pipe 97 is T'd into the pipe 95 and on the end remote from the T there is positioned a valve 98, which, in turn, is connected to another section of pipe 99. The pipe 99 is connected, by means of flanges or unions 101, to a section of pipe 102 joined to an expansion valve 103. A bulb 104, containing an expansible fluid thermostatically controls the operation of the valve 103.

10 A section of pipe 105 having a union or flange 106 interposed is joined to the valve 103 so that the expansion valve may be removed, in which case a section of pipe may be substituted and the operation of the system continued, by adjustment of the stop valve 98.

The section of pipe 105 is joined to a valve 107 so that when the valves 98 and 107 are shut, the valve 103 may be removed without the loss of any refrigerant within the system.

The valve 107 is joined to a section of pipe 108 which is T'd to a pipe 109, provided with flange 110 engaging a corresponding flange 111 on a pipe 112. The pipes 109 and 112 are bent, or formed in convolutions, as shown at 113 and 114 respectively, providing an evaporating coil. The pipes 109 and 112 empty into a header 115, made in two sections and provided with flanges 116, whereby it may be taken down or assembled. It will be observed that the well 89 is positioned in the header line 115 so that any refrigerant evaporating in the well 89 may readily pass off into the header. By this arrangement, no gas

pressure can occur in the well 89 to vary the liquid level therein from the level in either of the tanks 86 or 96. It will be observed that by means of the flanges 93, 94, 110, 111 and 116 the evaporating portion of the apparatus may be assembled in sections. Pipes 117, 117', 118 and 118' extend from the header 115 to the tanks 86 and 96.

To secure the highest efficiency in an apparatus of my type it is desirable that the refrigerant return to the adsorber-generator in the form of a gas, but frequently during the evaporating stage the volatilized refrigerant in rushing and bubbling through the evaporator coils may entrain some liquid. Should this occur in my apparatus, the pipes 117, 117', 118 and 118' and the well 89 will separate and drain off the liquid refrigerant before it reaches the adsorber-generator.

When the refrigerant is sucked or blown from the storage tank 49 to the secondary tanks 86 and 96, it is in a liquid phase, and is retained in the tanks 86 and 96 as a liquid, although during the refrigeration cycle there may be a limited evaporation in the secondary receivers. Still as a liquid, it passes from the tanks 86 and 96 to the expansion or regulating valve 103. After passage through the valve 103, the refrigerant is vaporized in the coils 113 and 114 and passes into the header 115.

Referring more particularly to Fig. 5, it will be observed that the tanks 86 and 96 are positioned near the top of the car, midway between the side walls, suitably supported by means not shown. Coils 113 and 114 extend from the secondary receiving tanks at an angle inclined to the horizontal. By inclining the coils 113 and 114 the liquid refrigerant can flow by gravity through the expansion valve 115. On evaporating, the refrigerant will rise through the evaporating tubes and return to the header. Supports, not shown, are provided for the evaporating coil in addition to the support received by reason of their connection to the secondary receivers.

Beneath the tanks 86 and 96 and the evaporating coils, there extends a baffle or deck 119, slightly inclined to the horizontal. Projecting downwardly from the lower end of the deck 119, adjacent the side wall 7, is a vertical baffle 121. The baffle 121 stops short of the floor 5 of the car, leaving an adequate space for the passage of air. The baffle 121 is boxed at the doors 13 in an air-tight fit. The deck 119 and baffle 121 are provided with a suitable insulating material 120, and on the top of the deck 119 and the side of the baffle 121 adjacent the wall 7 there is imposed a layer of tin, galvanized metal, or other appropriate material to prevent a collection of moisture on the insulation, thereby preserving its efficiency. The interior of the car is lined with galvanized metal, or some other suitable material 122. This preserves the

wood and heat insulation of the car. The metal 122 is curved at the various angles as at 123, 124, 125 and 126. In a refrigeration car it is essential that the air be circulated throughout the compartment in order to maintain the contents of the car free from decomposition or freezing. By providing the curves just described in the lining of the car there is prevented the formation of air pockets, and the circulation of air within the car is facilitated. As a further precaution against the formation of air pockets, an arcuate member 125' is provided at the angular junction of the vertical baffle 121 and the sloping deck 119.

Backs are provided on the floor of the car, made up of longitudinal spaced-apart runners, 127 and 128, secured to transverse beams 129 and 131. The beams 129 and 131 are hinged as at 132 and 133 respectively so that the racks may be raised to a vertical position and the car readily cleaned. These racks aid in maintaining the air in the car in a state of circulation and insure that all of the contents of the car are subjected to a constant draft of cooled air.

This particular arrangement of the evaporating section of the apparatus and the baffles and associated mechanism provide means whereby the air in the car is in constant motion. Air coming in contact with the secondary receivers 86 and 96 (which, as hereinbefore stated, provide a limited refrigerating effect by reason of the partial evaporation occurring therein), and the evaporating coils is chilled, and thereby increases in density. This chilled air then passes through the space between the baffle 121 and the side wall 7 of the car, and most of it is directed by the curved member 125 under the runners 127 and 128 and part of it is directed immediately upwardly into the car. The chilled air forced under the racks of the car rises within the car as it becomes warmer. There is therefore a steady draft maintained in the car, the warm air rising to the top, chilled by the tanks 86 and 96 and coils 113 and 114, descending to the floor and then repeating this cycle.

The header 115 is connected to the solenoid valve 43, which is adapted to allow the gaseous refrigerant to pass through the pipe section 45 and the pipe 23 into the adsorber-generator where it is taken up by the adsorbent when the latter is cool.

A tank 134 is provided with a removable cap 135 whereby it may be filled with a liquid such as alcohol, hydrocarbon oils or other liquid fuel, and is mounted adjacent the baffle 12 as shown in Figs. 1 and 12. A pipe 136 positioned in the bottom of the tank 134 is adapted to convey the liquid from the tank to a valve 137 of the solenoid type heretofore described and through pipe 138 to the pipe 42 where the liquid is discharged from the jet

39 and ignited by the spark plug 40 as heretofore described. A pipe 139 connected to a valve 141 is adapted to admit steam from a source of supply to a pipe 142, connected to the pipe 28 as heretofore described. The pipe 28 admits the superheated steam, or other medium to the coil 27. A suitable switch 143 is positioned within the compartment to regulate the flow of electricity through the wire 24 to the resistance coils 25. Although I refer herein to solenoid valves, under suitable circumstances valves of another type may be employed.

A storage battery 144 is provided to furnish electricity for the operation of the various solenoid valves. The electricity furnished the resistance coils 25 is preferably supplied to the valve 143 from a circuit other than the storage battery, the storage battery being used exclusively for the operation of the valves and spark plug. The resistance coil or heater is particularly adapted for use when the train is on a siding of an electrified system.

In Figure 6 there is shown a panel 145, on which are mounted a switch 146 to govern the electric switch 143, a switch 147 to regulate the fuel valve 137, a switch 148 to control the steam valve 141, push buttons 149 and 151 and a main switch 152. It is to be noted that these switches do not actually operate the valves, but merely tend to establish circuits that are finally closed when the tubes 66 and 91 are tilted in the appropriate direction.

There is shown in Fig. 12 a transformer 153 for use in connection with the spark plug 40. This transformer is of the conventional direct current type, and steps up the current sufficiently to operate the spark plug. It is shown fixed securely to the storage battery 144 but obviously its position may be altered should occasion demand.

From the foregoing, the operation of my device is apparent. If it is desired to use fuel as the heating medium, switches 146 and 148 are snapped to "off," and switch 147 is turned to "on," switch 152 is turned to "start" and button 151 is pushed in. Referring particularly to Figs. 12 and 13, and assuming that all the refrigerant in the system has been adsorbed in the adsorber-generator, the tanks 49, 86 and 96 are empty. The mercury bulb 66 (in tank 49) and the mercury bulb 91 (in well 89) are therefore tilted so that the mercury is in the "empty" ends of the tubes, as shown in Fig. 13.

A circuit is now established from the battery 144 to the center of the tube 91; from the "empty" end of tube 91 to the center of tube 66; from the "empty" end of the tube 66 across the shunted portion of the "open" solenoid of valve 143 (this valve having been snapped to "off" by switch 146); through the "open" solenoid of valve 137 (this valve hav-

ing been placed in operation by snapping switch 147 to "on"); shunted across the "open" solenoid of valve 141 (which was placed out of operation by turning the switch 5 148 to "off"); through the "closed" solenoid of valve 84 to the "open" solenoid of valve 44; through the "closed" solenoid of valve 43; to the thermostat 34; through the primary coil of the transformer 153 and 10 through the switch 152 back to the battery.

It will be observed that this circuit just described has opened the fuel valve 137, permitting the passage of fuel from the tank 134 through the pipes 136 and 138 to the jet 39 where it is dispersed in the pan 31. The transformer 153 builds up an induced current 15 in the secondary coil which is connected to the spark plug 40. The spark established by the plug 40 ignites the fuel emitted from the jet 39 and the heat is applied primarily to the base 17 of the adsorber-generator 14. The tubing 26 extending throughout the height of the adsorber-generator distributes this heat uniformly to the mass of adsorbent 25 contained in the tank 14. The shield 18 provides a means of confining the heat to the tank. The excess heat, not absorbed by the tank 14 and its contents, passes through the tubes 26 and out into the atmosphere through 30 the funnel 21.

The application of heat to the tank 14 and the adsorbent therein contained, drives off the adsorbed refrigerant. The circuit just described, it will be noted, closes the valves 35 43 and 84, preventing a passage of any refrigerant into the secondary receiving tanks 86 and 96. The valve 44 was opened by this circuit, and the refrigerant driven off from the adsorbent passes through the line 23, 40 valve 44 and pipe 46 into the condenser 47.

As has been stated, the condenser 47 is subjected to a draft of air entering the compartment between the insulated partition 12 and the end 4 of the freight car through the 45 screening 8. The wings 9 and 11 aid in directing the current of air into this compartment. The gaseous refrigerant, therefore, in passing through the condenser 47 is condensed and falls by gravity into the pipe 48, 50 thence into the tank 49. In driving off the adsorbed refrigerant in the form of a gas there is built up a pressure within that portion of the system between and including the adsorber-generator 14 and the tank 49. This 55 increased pressure facilitates the condensation of the refrigerant in the condenser.

As the tank 49 is filled with a liquefied refrigerant the float 78 within the well 56 rises on the rod 75. When the float 78 contacts with the upper bead 82, further upward 60 movement of the float 78 forces the tube 66 to pivot, and the mercury flows into the "full" end of the tube.

In the circuit first described electricity flows 65 for a sufficient length of time to operate the

various valves described. It would be undesirable, however, to continue the flow of current for any considerable period after the solenoids have been actuated, for there would result a waste of electrical current and the danger of burning out the solenoid windings. The provision I have made to prevent such results comprises the thermostat 34. This thermostat, it will be observed, is in series 70 with the transformer 153 which supplies the spark plug 40 with electricity. After the fuel dispersed from the jet 39 has been ignited, the further operation of the spark plug is useless. The thermostat 34, more specifically the finger 37, bends to the "hot" side of the well 33 when the temperature within the pan 31 has been raised, a short time after the fuel is ignited. In so bending, the circuit first described will be broken, and the further flow of current through the solenoids and transformer ceases. 75

When the bulb 66 flips to the "full" position with the filling of the tank 49, a new circuit is established. The amount of refrigerant within the system should be such that when it has been completely disengaged from the adsorbent, it will fill the tank 49. The float 78 therefore flips the mercury bulb 66 when there is no longer any refrigerant in 80 the adsorbent. As soon as the tank 49 is filled, the heating cycle is terminated. The apparatus is then ready for the refrigerating cycle. This is accomplished by the circuit that is established when the bulb 66 flips to the "full" position. Current flows from the 85 battery 144 to the center of the tube 91. It is to be noted that the tube 91 is still in the "empty" position, for all of the refrigerant driven off from the adsorbent has been directed to the tank 49 alone. From the center of the bulb 91 the current passes through the mercury to the "empty" end of the tube, and from the "empty" end of tube 91 to the center of tube 66. As the tube 66 has been flipped to the "full" position by the rise of refrigerant within the tank 49, the current passes from the center of the tube 66 through the "full" end of the tube to the "closed" solenoid of valve 143. The valve 143 was closed at the beginning of the refrigerating operation, and the current passing through the "closed" solenoid has no effect on the valve. From the valve 143 the current passes to the "closed" solenoid of valve 137, which is the fuel regulating valve. This valve was opened 100 by the first circuit, and inasmuch as it is desired to terminate the heating of the tank 14 and the adsorbent contained therein, the closure of this valve is necessary. From the valve 137 the current passes through the "closed" solenoid of valve 141, which valve has been closed since the beginning of the operation, and from there the current passes 105 through the "open" solenoid of valve 84. By 110

opening the valve 84 the liquid refrigerant 115 passes through the tube 85 to the adsorber-generator 14. The adsorbent 14, which has been 120 heated by the fuel dispersed from the jet 39, 125 now absorbs the liquid refrigerant. The adsorbent 130 is now saturated with liquid refrigerant and is ready for the refrigerating cycle.

from the tank 49 is allowed to pass into the pipe 85 and subsequently into the tanks 86 and 96. From the "open" solenoid of valve 84 the current passes to the "closed" solenoid of valve 44, and the tank 49 is therefore shut off from communication with the adsorber-generator 14. From the "closed" solenoid of valve 44 the current goes to the "open" solenoid of valve 43, and on opening this valve 10 the tanks 86, 96, their associated parts and the pipe 85, are in open communication with the adsorber-generator 14. After passing through the "open" solenoid of valve 43 the current travels to the circuit changer 150, 15 and thence back into the battery 144 by way of the switch 152.

By this circuit the supply of fuel to the jet 39 is cut off, and valve 44 is closed, throwing out of communication with the adsorber-generator 14 the tank 49. Valves 43 and 84 are opened and a clear passage to the adsorber-generator 14 is established from the pipe 85, tanks 86 and 96 and the header 115. The circuit changer 150 here employed, under suitable circumstances, may be of the conventional type, but due to the exigencies of the normal operation of my invention, I find it preferable to employ a circuit changer such as that described in my copending application 20 Ser. No. 250,744. In the case of this circuit changer, it is also desirable to allow the current to flow for only a short time, until the various valves have been thrown to either the "closed" or "open" position, and then to break 25 the circuit. This is accomplished by the circuit changer 150, which, after the operation of the valves, breaks the circuit and assumes a position whereby the circuit next to be described is established upon the bulb's 91 30 switching.

As has already been stated, during the heating cycle there is built up a pressure within the adsorber-generator 14, the pipes 23 and 46, the condenser 47 and the receiving tank 49. Inasmuch as the valves 43 and 84 are closed, this increased pressure does not extend to the rest of the system. When the valve 44 is closed by the circuit last described, therefore, the pressure within the condensing coil 47 and the tank 49 is the same as that pressure which existed within the adsorber-generator just prior to the closing of the valve. This same circuit, however, opens 45 valves 43 and 84 and with the cooling of the adsorber-generator 14, and the consequent reduction in pressure therein, the tanks 86 and 96 are also under a low pressure. It will be observed that the pipe 83 is joined to the 50 lowest part of the tank 49, and the high pressure existing in tank 49 is exerted upon the upper surface of the liquid refrigerant. The high pressure in tank 49, and the lower pressure in the tanks 86 and 96, therefore cause 55 the liquid refrigerant within tank 49 to be

forced through the pipes 83 and 85 and the valve 84, up into the tanks 86 and 96.

As above pointed out, the liquid refrigerant rises to the same height in the well 89 as obtains in the tanks 86 and 96. When the liquid in the tank 49 is withdrawn, the tube 66 is flipped to the "empty" position, and with the rise in the level of the liquid refrigerant in the well 89 the tube 91 is flipped to the "full" position. 70

The circuit now established is from the battery 144 to the center of the tube 91, and from the "full" end of the tube 91 to the "closed" solenoid of valve 84. By closing this valve 84 there is prevented the passage of any refrigerant between the tanks 49 and 80 86 or 96. It is now essential that no refrigerant pass from the tanks 86 and 96 to the tank 49, and that all of the refrigerant vaporized in tanks 86 and 96 be directed 85 into the header 115, and thence into the adsorber-generator 14. From the valve 84 the current passes to the circuit changer 150, which is in operative position opposite to that shown in Fig. 13, so that the current passes through the circuit changer and back to the battery 144. 90

As above pointed out, the liquid refrigerant in the tanks 86 and 96 extends through the pipes 92, 95, 97, 99 and 102. Assuming that the temperature of the car is sufficiently low, the valve 103 is closed. This valve is thermostatically controlled by the expandible fluid in the bulb 104. A valve either of the conventional expansion or regulating type or of the stop valve type may be employed here, but I have found it preferable to employ a valve of the latter construction, for very little pressure is required to either 100 open or close it. 105

As the pressure within the adsorber-generator 14, which pressure extends to the tanks 86 and 96, is decreased after the flame from jet 39 is extinguished, there is a limited evaporation of the liquid refrigerant in the tanks 86 and 96. Usually this evaporation is sufficient to maintain the car at a sufficiently low temperature to adequately preserve the freight. However, when the doors of the car have been opened, or in extremely hot climates, this vaporization in the tanks 86 and 96 must be supplemented. Therefore when the temperature in the car exceeds a predetermined point, the fluid in the bulb 104 110 expands and opens the valve 103. It is of course possible to regulate the valve 103 so that it is opened at any desired temperature. The refrigerant then passes into the coils 113 and 114, where there is a very pronounced evaporation. The increase in the amount of vaporization caused by the passage of the refrigerant into the coils 113 and 114 rapidly reduces the temperature within 115 the car, and when the predetermined tem- 120

perature is attained the valve 103 closes. The flow of refrigerant into the coils 113 and 114 is then ceased, and vaporization again restricted to the tanks 86 and 96.

5 One of the difficulties encountered in refrigerating processes or methods is the accumulation of frost and ice upon the evaporator coils and vessels. It is well known that any substance adhering to the evaporator vessels decreases the evaporator's efficiency, and the efficiency falls off sharply with any increase in the thickness. Now in this system it will be obvious that the evaporator coils 113 and 114 will free themselves 10 of coatings of ice and frost, due to the expansion valve stopping action within these coils at various times. The vessels 86 and 96 will also free themselves of any frost or ice during the heating period, which lasts any 15 where from one to three hours, depending upon the heating medium, temperature of the atmosphere and whether the car is in motion. During this heating period the warm air in the car will rise to the top and 20 serve to melt off the frost from the evaporator system, leaving these portions in a clean and highly effective state for further cooling action.

25 The drip which falls from the evaporator system is caught by the deck and carried away by a drain pipe, preferably of the water seal type, to the outside of the car, and allowed to drip on the roadbed. This drip being a clean water has no more deleterious effect upon railway structures than rain.

30 This removal of moisture from the car preserves the refrigerator car itself, its wood-work, insulation and frames, which, with the present iced method, involves expensive and continual service and repair work, due to the ravage and havoc wrought by the wet and dampness of ice, or of ice and salt. The drip-page of the latter combination is so deleterious to railway structures that the waste drip must be preserved, and its useless weight transported until the refrigerator car arrives at an icing and dumping station where the brine is disposed of and a new charge of 35 ice and salt placed in the bunkers.

40 By my method of refrigeration the freight cars need not be stopped, from the time of loading to the time of arrival at destination, for the fuel tank and steam supply are more than sufficient to keep the car and its contents at a low temperature over long periods of time.

45 As vaporization occurs in the tanks 86 and 96, the liquid refrigerant contained therein is depleted, and when the float in the well 89 contacts with the lower bead on the rod 75, the mercury bulb 91 is flipped to the "empty" position. It will be remembered that with the cessation of the heating cycle, all of the 50 liquid refrigerant in tank 49 was forced to

the secondary receivers 86 and 96, and the mercury bulb 66 was consequently thrown to the "empty" position. The circuit now established is the same as the circuit first described in the operation of the device. All of the refrigerant has been taken up by the adsorbent in tank 14, and a new heating cycle is established by the circuit now in effect. The complete refrigerating process, as just described, is repeated as may be necessary 55 to maintain the interior of the car at a uniform and predetermined temperature.

60 The apparatus just described is particularly adapted for use in freight cars or other transportation vehicles containing perishable commodities. The refrigeration effected by this apparatus insures a uniform temperature, maintainable within very narrow limits. It will also be observed that the coils 113 and 114, controlled by the valve 103, quickly cools the vehicle when necessary; and when the desired temperature is obtained, the evaporation within the tanks 86 and 96 serves to maintain that temperature 65 over a considerable period.

70 Other types of cars, or vehicles, particularly where they contain commodities that do not have to be maintained at such a constant or closely controlled temperature may be cooled by means of an apparatus such as shown in Figures 14 to 18. Figure 14 shows the refrigerating apparatus within that portion of the car bounded by the end 3 and the partition 12. The adsorber-generator, condenser and associated mechanism are omitted from these figures.

75 In this alternative form of apparatus, there is provided a receiving tank 154, positioned near the top of the compartment, and supported by suitable means not shown. Into this tank the pipe 85 shown in Fig. 12, empties. Condensed refrigerant is forced through the pipe 85 into the receiving tank 154 by means of the high pressure in tank 49. The tank 154 is provided with a well 155, in 80 which there is positioned the same type of float, mercury bulb and associated mechanism shown in Fig. 8. The tank 154 takes the place of the receivers 86 and 96, but as 85 will be observed in Fig. 15, the tank 154 extends transversely across the car.

90 Into the base of the well 155 there is suitably secured a pipe 156. At the opposite end of the pipe 156 there is positioned a valve 157, controlled by an expandible fluid contained in a bulb 158. Liquid refrigerant from the tank 154 flows through the pipe 156 to the valve 157. When the valve is opened the liquid passes into a pipe 159, which is joined to the outlet side of the valve. The pipe 159 extends to the floor of the car and a T joint (not shown) is provided at this lower end, connecting to a pipe 161 and a coil 162. The coil 162 is held in an upright position by means of a bracket 163 affixed to the partition 95

12 of the car. A pipe 164 conducts the fluid from the coil 163 to the tank 154. It will be observed that the pipe 164 extends to approximately the top of the tank 154 as at 165. This end 165 of the pipe 164 is above the inlet pipe 85, the reason therefor appearing hereinafter. The coil 162, as shown in Fig. 15, extends substantially the width of the car, but under suitable circumstances there may be substituted for this single coil several coils in parallel.

10 At the end of the car opposite the tank 154 there may be a coil similar to 162 or a plurality of coils 166, connected in parallel to the pipe 161 may be used. Referring to Fig. 16, it will be observed that I have herein shown four coils spaced apart across the width of the car, but under suitable circumstances this particular arrangement may be 20 varied. Fig. 17 shows a top view of the arrangement depicted in Fig. 16, in which the coils are spaced apart.

25 However, in order to obtain a more pronounced refrigeration, an arrangement of the coils 166 may be made such as shown in Fig. 18. In this figure it will be observed that the coils 166 intermesh, providing a greater number of coils within a given area, and hence a greater refrigerating effect. As stated, the 30 particular arrangement is optional, depending upon the conditions of operation, and the temperatures desired.

35 The upper ends of the coils 166 are joined to a pipe 167 which extends across the car. This pipe is connected to a pipe 168 which empties into the tank 154.

40 As the liquid refrigerant passes through the pipe 159 a portion of it is diverted to the coil 162 and the remainder to the pipe 161, and then to the coils 166. Within the coils there is a greater vaporization than occurs within the tank 154, or the pipe 161. The refrigeration therefore is obtained at the ends of the cars.

45 As stated in connection with the other form of apparatus, it is essential that the air within the car be kept in a state of free circulation. Ordinarily there is a tendency for stratification of the air within a closed refrigerating compartment, the lower part of the compartment being always at a lower temperature than the upper section.

50 To aid in maintaining a circulation of air, I have provided a baffle 169, suitably supported adjacent the tank 154 and pipe 159. A space 171 is left between the top of the baffle 169 and the roof 1 of the car. A similar space 172 is provided between the bottom of the baffle 169 and the floor 5, so that air from 55 the main body of the car can pass into the compartment between the baffle 169 and the partition 12. A baffle 173, similar to the baffle 169, is provided at the opposite end of the car adjacent the coils 166. A space 174 is left at the top and a similar space 175 at

the base of the baffle 173. The car here shown is lined with galvanized or non-corrodable metal 122 as in the case of the first apparatus, and at the ends of the car is curved as at 176. As before described, these curvatures of the 70 lining prevent the formation of air pockets.

75 The arrows indicate the currents of air established by reason of these baffles, and it will be observed that air coming in contact with the tank 154 in which there is partial vaporization, and the coils 162 and 166, falls to the bottom of the car and is forced out through the openings 172 and 175 into the body portion of the car. This air circulates through the lower layers of the contents, and on absorbing the heat of the contents rises toward the top of the car. As the air that comes in contact with the refrigerating device is constantly sinking, there is established a current of air by means of which the hotter air in the top of the car is sucked through the openings 171 and 174 where it is cooled.

80 The operation of this device is similar to the operation of the form of apparatus first described. After the liquefied refrigerant is introduced to the tank 154 from the pipe 85, and assuming that the valve 157 is closed, there is collected in the tank 154 a body of liquefied refrigerant. Assuming that the temperature is sufficiently low within the car to 85 obviate the necessity of any great degree of cooling, on termination of the heating cycle the condensed refrigerant in tank 154 partially evaporates. The refrigeration thus produced tends to maintain the temperature 90 of the car sufficiently low, even though this refrigerant is concentrated at one end of the car.

95 Should the temperature within the car rise above a predetermined point, the fluid contained in bulb 158 expands and opens the valve 157. I have shown the bulb 158 mounted on the baffle 169, although under suitable circumstances this bulb may be positioned at 100 some other part of the car, such as in the center. On opening the valve 157 the liquid refrigerant passes through the pipe 159, and is introduced directly into the coil 162 and also, through the pipe 161, into the coils 166. Within the coils 162 and 166 there is a more rapid vaporization than occurs within the tank 154. A greater refrigeration effect is 105 therefore produced, and it will be observed that by having the coils 162 and 166 at the ends of the car there is obtained a more uniform cooling.

110 After vaporization of the refrigerant in the coils 162 and 166, the gaseous refrigerant passes by the tubes 164 and 168 back into the tank 154. In vaporizing it frequently occurs 115 that a portion of the liquid refrigerant is entrained in the gas, and this liquid refrigerant may either fall back into the coils 162 and 166, or be carried over into the tank 154. The 120 particular arrangement of the tubes 164 and 125

168 in the tank 154 insures that any entrained liquid refrigerant will be separated from the gaseous refrigerant, the gas remaining at the top of the tank and passing out through the pipe 177, while the entrained liquid will fall to the bottom of the tank or surface of the body of liquid contained in the tank. In view of the fact that the pipe 85 enters the tank below the ends of the pipes 168 and 164, there is little opportunity for the gaseous refrigerant to enter the pipe 85. Even if it did, the valve 84, closed during the evaporating step, will prevent its passage into the tank 49.

The vaporized refrigerant passes by way of the pipe 176 to the valve 43, shown and described in connection with the first form of apparatus. It will be remembered that during the evaporating cycle, the valve 43 will be open, allowing the passage of the gaseous refrigerant into the adsorber-generator 14 where it is taken up by the adsorber. Upon adsorption of all of the gaseous refrigerant the apparatus is in condition for the heating cycle. When the refrigerant in the tank 154 and the coils 162 and 166 has been evaporated, the mercury bulb in the well 155 will flip to the "empty" position, establishing the necessary circuit for the heating operation.

The same electrical hookup is used with the modified form of apparatus as that employed in connection with the apparatus shown in Figure 12. For the modified form, the mercury bulb within the tank 155 correspond to, and functions the same as bulb 91 in the well 89.

In both of the types of apparatus, it is of course obvious that although I have described the operation of the invention when using fuel as a heating means, either steam or electricity may be employed. The switches indicated in Fig. 6 on the panel 145 will be appropriately turned so that the desired heating medium is used. Referring to Fig. 13, the switch governing the heating medium that is being used is open, so that the current passes through the open solenoid of the valve controlling that medium. The other switches are closed and the current is shunted over the valve. Under certain circumstances it may be desirable to expedite the heating cycle, in which event more than one of the heating mediums may be employed. This, of course, is easily accomplished by my invention.

It will be apparent that both of the forms of refrigerating apparatus herein shown and described are economical as to the amount of space required. This, of course, is an important feature in any refrigerating apparatus, but assumes particular significance when applied to refrigerating devices for freight cars or other vehicles adapted for the transportation of goods. The space occupied by any refrigerating apparatus is so

much space deducted from the total amount of commodities that might be transported.

It is to be noted that the apparatus which is the subject of this application is simple and economical to construct, and is provided with a minimum of parts. The various elements of the device are sturdy and capable of withstanding the shocks incident to transportation. The baffles 53 provided in the various tanks employed in my apparatus, prevent a surge of the liquefied refrigerant and a slopping over into other parts of the apparatus not adapted for the liquid phase. Because there are few moving parts, there is consequently little opportunity for wear in the apparatus.

It will be observed that my invention is automatic, and once having been set in operation requires no attention. This automatic feature is not at the expense of efficiency, for I have devised means for maintaining the temperature at a uniform and constant level and any variations from this temperature are immediately compensated for by the amount of refrigeration produced by my apparatus.

I have shown my invention with reference to a freight car, and while I have referred specifically to its application in such a field, it is of course appreciated that its use is not confined thereto, for it may readily be installed in vans, boats and other carriers.

While I have referred herein to an adsorption apparatus, the words adsorption and adsorbed are not to be taken as limiting the scope of this invention, for an adsorbent, adsorbent, or combination adsorbent and adsorbent may be employed in this device.

It will be appreciated that various modifications may be made in the apparatus herein depicted and described, without exceeding the scope of my invention as defined in the appended claims, it being distinctly understood that only the prior art and claims herein are to be definitive of my invention.

I claim:

1. A freight car comprising a car body, a refrigerating unit mounted within the car including an air cooled condenser, and means on the car body to deflect air from without the car body into heat exchange relationship with the condenser when the car is moving in either direction.

2. In combination with a freight car a refrigerator comprising an adsorber-generator positioned adjacent one end of the car body, a condenser adjacent the generator and in fluid communication therewith, and means to induce a flow of cooling air upon the condenser from the air stream outside the car when the car is moving in either direction.

3. A refrigerating car comprising a car body, an adsorber-generator mounted adjacent one end of the car, a vertically disposed condenser coil connected with the generator,

and plurality of inclined receivers connected with the condenser, and a plurality of evaporating coils connected with the receivers and extending transversely of the car adjacent to the top.

4. A refrigerating car comprising a car body, heat insulating means to exclude an exchange of heat between the interior and exterior of the car, all of the interior corners of the body being filleted to positively prevent the formation of any air pockets, and refrigerating means within the car body adapted to maintain the air in circulation.

5. In a freight car, a deck adjacent the top of the car, a vertical baffle to maintain the air within the car circulating, a refrigerant receptacle mounted above said deck, an evaporating coil connected with said receptacle and adapted to cooperate therewith to induce a circulation of air in said car.

6. A refrigerating apparatus for a vehicle comprising an adsorber-generator, means to heat the adsorber-generator internally and externally, a condenser adapted to receive and condense a refrigerant from the adsorber-generator, a tank adapted to receive the condensate, means to maintain the condensate in the tank until termination of the application of heat to the adsorber-generator, means to convey the refrigerant from the tank to evaporating chambers when heat is withdrawn from the adsorber-generator, and means to permit the passage of the refrigerant from the evaporating chambers to the adsorber-generator after termination of the heating of the adsorber.

7. A refrigerating apparatus comprising an adsorber-generator, a condenser, a condensed refrigerant receiver and means connected with said receiver for receiving refrigerant to be evaporated, said receiver comprising a tank, a plurality of baffles in said tank and means in said tank operated by the variation in the liquid level therein for controlling the operation of said adsorber-generator.

8. A refrigerating apparatus comprising an adsorber-generator, a condenser, a condensed refrigerant receiver and means connected with said receiver for receiving refrigerant to be evaporated, said means for receiving liquid to be evaporated comprising a plurality of angularly arranged receptacles, communicating with a well, and float operated means in said well for controlling the operation of said adsorber-generator.

9. A refrigerating apparatus comprising an adsorber-generator, a condenser, a condensed refrigerant receiver and means connected with said receiver for receiving refrigerant to be evaporated, said receiver comprising a tank, a plurality of baffles in said tank and means in said tank operated by the variation in the liquid level therein for controlling the operation of said adsorber-

generator, said means for receiving liquid to be evaporated comprising a plurality of angularly arranged receptacles communicating with a well, and float operated means in said well for controlling the operation of said adsorber-generator.

10. In a refrigerating apparatus a source of gaseous refrigerant, means for condensing said refrigerant and means for conveying said condensed refrigerant to evaporating means, said evaporating means comprising a plurality of communicating tanks, a conduit connected with said tanks adapted to convey refrigerant to a plurality of evaporating coils, a conduit for returning gaseous refrigerant to said source and means connecting said coils and the upper portions of said tanks with said conduit.

11. A refrigerating car comprising a car body, a refrigerating unit mounted within a compartment of the car including an air cooled condenser, said compartment having communication with the atmosphere through a wall of said car, and angularly arranged baffles adapted to deflect air over said air cooled condenser regardless of the direction of movement of the car.

12. A refrigerating car comprising a car body having a compartment therein, a refrigerating unit mounted within said compartment including an air cooled condenser, said compartment having communication with the atmosphere through a screened wall, and baffles mounted adjacent said screened wall for deflecting air into said compartment regardless of the direction of movement of the car.

13. A refrigerating car comprising a car body having an adsorber-generator mounted adjacent one end of the car, a vertically disposed condenser coil connected with the generator, a plurality of inclined receivers connected with the condenser, a plurality of evaporating coils connected with the receivers and a conduit for returning the evaporated refrigerant to said adsorber-generator and means for connecting said coils and the upper portion of said inclined receivers with said conduit.

14. In a refrigerating car an inclined deck, adjacent the top of the car and spaced from the side walls thereof, a vertical baffle connected with said deck and spaced from the walls of said car, a pair of inclined refrigerant containers mounted above said deck and a plurality of evaporating coils connected with said containers and extending transversely of the car above said deck.

15. A refrigerating apparatus for a vehicle, comprising an adsorber-generator, a condenser connected with the adsorber-generator, and adapted to condense a refrigerant, a tank adapted to receive the condensate, means to pass the condensate from the tank to evaporating chambers, and means to convey the

evaporated refrigerant to the adsorber-generator, said chambers comprising a plurality of angularly arranged communicating tank structures and means between and communicating with said tanks for controlling the operation of said adsorber-generator.

5 In testimony whereof I affix my signature.

LEONARD KAY WRIGHT.
